FOREIGN PATENT DOCUMENTS

GB 2070770 S * of 1899

* cited by examiner

Primary Examiner—Gary D. Watson*Assistant Examiner*—T. Chase Nelson*(74) Attorney, Agent, or Firm*—Brinks Hofer Gilson & Lione(57) **CLAIM**

I claim the ornamental design for an impact drill, as shown and described.

DESCRIPTION

FIG. 1 is a top perspective view of first embodiment of an impact drill of the present invention;

FIG. 2 is a first side view thereof;

FIG. 3 is a second side view thereof;

FIG. 4 is a top view thereof;

FIG. 5 is a bottom view thereof;

FIG. 6 is a front view thereof;

FIG. 7 is a rear view thereof;

FIG. 8 is a top perspective view of a second embodiment of an impact drill of the present invention;

FIG. 9 is a first side view thereof;

FIG. 10 is a second side view thereof;

FIG. 11 is a top view thereof;

FIG. 12 is a bottom view thereof;

FIG. 13 is a front view thereof;

FIG. 14 is a rear view thereof;

FIG. 15 is a top perspective view of a third embodiment of an impact drill of the present invention;

FIG. 16 is a first side view thereof;

FIG. 17 is a second side view thereof;

FIG. 18 is a top view thereof;

FIG. 19 is a bottom view thereof;

FIG. 20 is a front view thereof;

FIG. 21 is a rear view thereof;

FIG. 22 is a top perspective view of a fourth embodiment of an impact drill of the present invention;

FIG. 23 is a first side view thereof;

FIG. 24 is a second side view thereof;

FIG. 25 is a top view thereof;

FIG. 26 is a bottom view thereof;

FIG. 27 is a front view thereof; and,

FIG. 28 is a rear view thereof.

Any broken lines in the drawings are for illustrative purposes only and form no part of the claimed design.
